UNITED STATES PATENT OFFICE.

HARRY WALKER, OF WILMINGTON, DELAWARE, ASSIGNOR OF ONE-HALF
TO SAMUEL C. BIDDLE, OF SAME PLACE.

DOOR-CHECK.

SPECIFICATION forming part of Letters Patent No. 364,616, dated June 7, 1887.

Application filed April 27, 1887. Serial No. 236,291. (No model.)

To all whom it may concern:

Be it known that I, HARRY WALKER, a citizen of the United States, residing at Wilmington, in the county of New Castle and State of Delaware, have invented certain new and useful Improvements in Door-Checks; and I do hereby declare the following to be a full, clear, and exact description of the invention, such as will enable others skilled in the art to which it appertains to make and use the same.

My invention relates to the class of devices used for holding doors ajar; and it consists, essentially, of a lever pivoted to the door and carrying on one of its arms a brake which is adapted to be pressed upon the floor to hold the door by friction in any desired position.

In the accompanying drawings, which illustrate my invention and form a part of this specification, Figure 1 represents my improved check applied to a door and the latter secured in partly-opened position. Fig. 2 represents a front elevation of the check applied to a door, the full lines and dotted lines, respectively, showing the brake in and out of operation. Fig. 25 3 represents a section on the line 1 1, Fig. 2.

A designates a base-plate, which is secured to the door near the bottom and preferably near the front edge, as illustrated in Fig. 1. To this base-plate is pivoted a vibrating or 30 swinging lever, B, the lower end of which carries a brake, C, to be pressed upon the floor to hold the door by friction in any desired position.

The upper end of the lever B is forked, the 35 two branches b b' standing at approximately right angles to each other in the plane of vibration. The ends of these branches are bent out, so as to be conveniently operated by the foot in applying or releasing the brake.

40 The brake C consists of a wheel journaled to the lower end of the lever B, and is adapted to roll on the floor in applying or releasing the same. The wheel is provided with a rubber band or tire, c, which is seated in a groove in the periphery, as shown in Fig. 3, and which forms an elastic bearing-surface.

The base-plate A has an outturned flange, a, along a portion of its lower edge, which forms a stop for the lever B. This flange terminates

at a point which allows the lower end of the 5c lever to be turned slightly past the vertical center, as represented in Fig. 2, whereby the brake is retained in position and is prevented from becoming accidentally unfastened. When the brake is released, the flange a forms a support for one of the arms of the lever, to prevent the same from being turned far enough to strike the floor.

The upper end of the lever B is forked merely for the purpose of enabling it to be 60 operated conveniently with the foot. Obviously, the operation would be the same if a straight lever were used instead of the forked lever shown and described, and such a lever is therefore to be regarded as falling within 65 the scope of my invention.

The device constructed as shown and described is adapted to be used also as a sash-fastener. In applying it to this purpose it is preferably attached to the top of the lower sash, 70 so that the brake may be applied to the side rail of the upper sash to fasten the two sashes together; or it may be attached to the window-frame to fasten either sash alone.

Having thus described my invention, I 75 claim—

1. In a door-check, the combination of the base-plate A, adapted to be secured to a door and provided with a flange, a, the lever B, pivotally connected with said base-plate, and the brake C, journaled on the lower end of the lever, the said flange a forming a stop and support for the lever, substantially as shown and described.

2. In a door-check, the combination of a 85 base-plate, A, adapted to be secured to a door and provided with a flange, a, the three-armed lever B, pivotally connected with said base-plate, and a brake, C, journaled on the lower end of the lever, the said flange a forming a 90 stop and support for the lever, substantially as shown and described.

In testimony whereof I affix my signature in presence of two witnesses.

HARRY WALKER.

Witnesses:

JAMES O'TOOLE,
SAM'L. C. BIDDLE.
